UNITED STATES PATENT OFFICE

BERNARD LUSTGARTEN, OF NEW YORK, N. Y.

MEANS FOR SECURING TAPES TO GARMENTS

Application filed February 14, 1931. Serial No. 515,731.

My invention relates to means for attaching removable and adjustable straps or tapes to garments and it is my object to produce such means in a neat, quick and inexpensive manner and in which any desired adjustment of length may be quickly and easily made and in which the metal portion of the adjusting means will be buried or enclosed in fabric in such manner that it will be entirely concealed and kept out of contact with the body and garments of the wearer. If straps of a different color are to be substituted or if the straps or tapes attached to the garment are soiled, or if they are elastic, containing rubber, they may be quickly and easily removed from the garment when it is washed and later replaced. My invention is particularly applicable to the supporting shoulder straps of garments and the like and to garters and the like which are to be attached to or removed from a garment.

In the drawing Fig. 1 is a plan view, partly broken away, of my improved securing means; Fig. 2 a sectional view of the structure of Fig. 1 on the line 2—2 thereof; Fig. 3 a plan view of my metal clip about to be attached to a strap; Fig. 4 an edge view of the clip on a strap before the clip has been closed; Fig. 5 a perspective view of my clip; and Fig. 6 a view of a modified form of loop used in carrying out my invention.

To practice my invention a short piece of fabric 1 is sewed, or otherwise attached, to the edge or adjacent the edge of a garment 2 to form a loop. It may be attached directly to the garment or it may be attached to a tape which is later sewed to the garment, the result being the same in either case.

This loop 1 is substantially as long as the strap to be secured is wide but the edge against which the pull of the strap or tape is exerted is contracted or narrowed. This contraction may take the form of inwardly extending tack stitches 3—3 as shown in Fig. 1, or converging lines of stitches 3'—3' as shown in Fig. 6 or in any other desired manner. In Fig. 6 the loop 1' is sewed to the tape 2' by means of the converging lines of stitches 3'—3', as above described.

A metal clip 5 is formed with two integral

faces 6 and 7 with a slot at their meeting edges, the metal at the ends of the slot forming shoulders or abutments. One face 6 may be provided with inwardly extending fabric engaging prongs 9 and the other face 7 may be provided with co-operating apertures 10. Other fabric engaging means may be substituted for the prongs and apertures without departing from my invention. The ends of the clip are preferably curved to allow easy entrance into the loop or pocket. In use the clip 5 is slightly spread as shown in Figs. 3 and 5 and the strap or webbing 11 to be attached to the garment is slipped through the slot 8. The faces of the clip are then pressed together so that the fabric engaging means, (prongs and apertures being shown) will engage the fabric. The strap may then be cut off flush with the end of the clip opposite the slot.

When the strap 11 is to be adjusted for length the clip end is pulled out of the loop or pocket, the clip 5 spread slightly and slid to any desired position on the strap after which it is again closed down to engage the strap and the strap and clip pulled into the pocket.

By this construction the loops may be sewed to the garment by an automatic sewing machine, the metal clips slipped on the straps and clinched and the straps passed through the loops quickly, easily and cheaply. The length of the straps may be adjusted to any desired point, no matter how small, and the metal clip is buried in the fabric so that it cannot come into contact with the skin or garments of the wearer.

I claim:—

1. Means for connecting straps and garments, comprising a loop secured to a garment, said loop being contracted at one edge, a clip composed of integral plates provided with a slot at their meeting edges, the parts adjacent the slot ends forming shoulders, a strap passing through said clip slot, means on said clip engaging said strap, said strap and clip being passed under said loop with the shoulders on said clip abutting against the contracted edge of the loop.
2. Means for connecting straps and gar- 100

ments, comprising a loop secured to a garment, a line of stitches securing the ends of said loop to the garment, tack stitches extending inwardly from the lines of stitches 5 to contract the loop opening at one edge, a clip composed of integral plates provided with a slot at their meeting edges, the parts adjacent the slot ends forming shoulders, a strap passing through said clip slot, means 10 on said clip engaging said strap, said strap and clip being passed under said loop with the shoulders on said clip abutting against the tack stitches.

In testimony whereof I have affixed my
15 signature.

BERNARD LUSTGARTEN.
